UNITED STATES PATENT OFFICE.

HENRY F. DENY, OF MARYDEL, MARYLAND.

MOTOR.

Application filed September 30, 1925. Serial No. 59,664.

This invention relates to an internal combustion engine, the general object of the invention being to increase the efficiency of the engine by eliminating the crank shaft, 5 the fly wheel, timing gears, the valves and the tappets and other parts.

Another object of the invention is to provide a ring-shaped cylinder which forms an annular path for two sets of pistons, with 10 means for first causing one set to act as abutments for the expanding gases of the exploded charges of fuel, so that these gases will act on the pistons of the other set to give them their propulsion stroke and then 15 to cause the pistons of the second set to act as abutments, so that the gases of the new charges will act against the pistons of the first set. Thus the pistons will be given a step by step movement around the circular 20 path formed by the cylinder, first one set moving under the action of the expanding gases and then the second set.

Another object of the invention is to provide novel means for transmitting the movements of the pistons to a shaft which passes through the center of the device.

This invention also consists in certain other features of construction and in the combination and arrangement of the several 30 parts, to be hereinafter fully described, illustrated in the accompanying drawings and specifically pointed out in the appended claims.

In describing my invention in detail, 35 reference will be had to the accompanying drawings wherein like characters denote like or corresponding parts throughout the several views, and in which:—

Figure 1 is a side view looking toward 40 one side of the device.

Figure 2 is a similar view, but looking toward the other side.

Figure 3 is an elevation with one portion of the casing removed.

45 Figure 4 is a section on line 4—4 of Figure 1.

Figure 5 is an elevation with parts broken away, of the two plates which carry the pinions.

50 Figure 6 is a sectional view showing the connection between a piston and its supporting plate.

Figure 7 is a view of one of the piston carrying plates.

55 Figure 8 is an enlarged sectional view through a portion of one of the pinions,

its supporting plates and the piston carrying plates.

Figure 9 is a face view of one of the pinions.

Figure 10 is an edge view of the pinion. 60 In these views, 1 indicates a casing which is formed of two parts bolted together and which forms an annular cylinder 2, provided with the water jacket 3, and the chamber 4 which is surrounded by the cylinder or chamber 2, the two chambers being in communication with each other by the annular opening 5 which is formed in the dividing wall between the two chambers. A shaft 6 passes through the center of the casing, 65 which is provided with the central bosses 7 provided with the passages for the shaft and having the ball bearings 8 and the packing glands 9 for said shaft. The bosses 70 are provided with the base parts 10 which are designed to engage suitable supports for holding the device in upright position. A plate 11 is arranged within the chamber 4 and is fastened to the shaft by its boss 12 75 and a second plate 13 is bolted to the plate 11. The plate 13 is of ring shape and surrounds a gear 14 which is bolted to an interior boss 15 on one of the sections of the casing. Plate 13 is also provided with four 80 recesses 16 for receiving pinions 17 which engage the gear 14 and which are rotatably supported by the plates 11 and 13 by having their hubs 18 engaging aligning openings 85 in the plates, ball bearings 19 being arranged in the openings to provide anti-friction means for the hubs of the pinions. Each hub of each pinion is provided with a crank pin 20 on which is placed a roller 21, roller bearings 22 being provided for each roller. A pair of saucer 90 shaped plates 23 and 24 are arranged in chamber 4 and have their flanges 25 abutting and extending into the slot 5. These plates extend over the plates 11 and 13 and the pinions carried thereby and each saucer-shaped plate is provided with a large central opening 26 and four slots 27 which have their inner ends in communication with the opening. The slots 27 receive the rollers 21 95 on the crank pins of the pinions, and attention is called to the fact that the crank pins of each pinion are arranged diametrically opposite each other on opposite faces of the pinion so that one pin extends into a slot 27 of the plate 23, and the other pin will extend into a slot 27 of the plate 24, as 100 105 110

2 shown in Figure 4. Each of the plates 23 and 24 is provided with the ears 28 which extend into the cylinder or chamber 2, and the arc-shaped pistons are attached to these 5 ears by the pins 29. Four pistons 30, 31, 32 and 33 are connected with the plate 23, and four pistons 30', 31', 32' and 33' are connected with the plate 24. A spark plug 34 is in communication with the top of the 10 cylinder and a plug 35 is in communication with the lower part of the cylinder. Elongated exhaust ports 36 and 36' are arranged at diametrically opposite points in the cylinder and similar-shaped inlet ports 37 and 15 37' are arranged at diametrically opposite points in the cylinder. The inlet ports are connected together by the inlet manifold 38 and a suitable manifold may be connected with the exhaust ports.

20 From an inspection of Figure 3, it will be seen that when the charges at the top and bottom of the cylinder are fired by the spark plugs, the cylinders 30 and 32 of plate 23 will be given their propulsion stroke by 25 the expanding gases, and in this movement, the plate 23, bearing against the rollers of the crank pins of the upper and lower pinions, will cause the pinions to travel around the gear 14, and as the inner crank 30 pin of each of the upper and lower pinions moves in an arc in the slot of the plate 24, this plate and its pistons are prevented from having rearward movement from the pressure of the gases, but is given a slight forward movement, so that the pistons of plate 35 24 will take the positions formerly occupied by the pistons of plate 23, while said pistons of the plate 23 will move to a position formerly occupied by the pistons of plate 24.

40 In other words, the piston 30 of plate 23 will move to the position formerly occupied by the piston 31' of plate 24, while piston 31' of plate 24 is moving to the position formerly occupied by piston 30 of plate 23.

45 On the next action, the plate 24 and its pistons will move to a greater extent than the plate 23 and its pistons. Thus the plates and the pistons are given a step by step rotary movement, first one set of pistons moving to a greater extent under the 50 propulsion action of the expanding gases, while the pistons of the other set act as abutments and move to a lesser extent. Then these last mentioned pistons will move to a great extent under the propulsion action of the expanding gases, the first set acting as the abutments and moving to a lesser extent. As piston 30 moves ahead on its 55 propulsion stroke, it will force the previously exploded gases out of the exhaust 36, while the piston 31' is uncovering said exhaust passage 36 and covers the inlet 37. At the same time, piston 32' is sucking in the explosive charge through the inlet 37 and this 60 charge will be compressed between the pistons 31 and 32' on their next movement of the pistons. At the end of the compression action, piston 32' will occupy the space now occupied by piston 32 and piston 31 will occupy the space now occupied by piston 32'. The movements of the pinions will be communicated to the plates 11 and 13 and thus to the shaft.

65 As will be seen, the action of the device is double, that is, there are two explosive actions, two exhaust actions and two suction actions taking place at the same time.

A pipe 39 connects the upper and lower portions of the water jacket together, and a second pipe 40 connects the two side portions of the jacket together, the pipe 39 being provided with a discharge outlet 41 which is adapted to be connected with the inlet of the pump, and the pipe 40 is provided with an inlet 42 which is connected with the outlet of the pump. Thus water is introduced into the water jacket at the coolest points of the motor and is taken from the jacket at the hottest points thereof.

70 It is thought from the foregoing description that the advantages and novel features of my invention will be readily apparent.

I desire it to be understood that I may make changes in the construction and in the combination and arrangement of the 75 several parts, provided that such changes fall within the scope of the appended claims.

What I claim is:—

1. A motor of the class described, comprising a casing having an annular chamber therein and an inner chamber, a shaft passing through the casing, a member fastened to the shaft and having holes therein, pinions rotatably mounted in the holes, a stationary gear in the casing meshing with the pinions and around which said pinions travel, each pinion having a crank pin at each side thereof, the pins being arranged at opposite points on the pinion, a pair of saucer shaped plates enclosing the outer periphery of the pinion carrying member, each plate being slotted to receive the crank pins of the pinions and each plate having portions extending into the annular chamber, a set of pistons connected with each plate, one set being alternately arranged with respect to the other set, the chamber having inlet and exhaust ports in its walls which are controlled by the moving pistons and ignition means associated with the chamber.

2. A motor of the class described, comprising a casing having an annular chamber therein and an inner chamber, a shaft passing through the casing, a member fastened to the shaft and having holes therein, pinions rotatably mounted in the holes, a stationary gear in the casing meshing with the pinions and around which said pinions

travel, each pinion having a crank pin at each side thereof, the pins being arranged at opposite points on the pinion, a pair of saucer shaped plates enclosing the outer periphery of the pinion carrying member, each plate being slotted to receive the crank pins of the pinions and each plate having its outer periphery forming a part of the wall of the annular chamber with projections on 10 the plate extending into the annular chamber, a set of pistons connected with the projection of each plate, one set being alternately arranged with respect to the other set, the chamber having inlet and exhaust ports in its walls which are controlled by the moving pistons and ignition means associated with the chamber.

In testimony whereof I affix my signature.

HENRY F. DENY.
